UNITED STATES PATENT OFFICE.

ROBERT GOOD, OF WASHINGTON, PENNSYLVANIA, ASSIGNOR OF ONE-HALF TO HAZEL-
ATLAS GLASS COMPANY, OF WHEELING, WEST VIRGINIA, A CORPORATION OF
WEST VIRGINIA.

LEER.

Application filed January 27, 1923. Serial No. 615,360.

To all whom it may concern:

Be it known that I, ROBERT GOOD, a citizen of the United States, residing at Washington, in the county of Washington and 5 State of Pennsylvania, have invented new and useful Improvements in Leers, of which the following is a full, clear, and exact description.

The invention relates to leers for annealing glassware, and more particularly to a vertical leer construction of comparatively small cross sectional area which results in a great saving of floor space.

One of the objects of the invention is to 10 provide a leer so constructed that it will reduce to a minimum the amount of auxiliary heat necessary, and in some cases, particularly heavy ware, possibly eliminating the use of auxiliary heat altogether.

20 Another object of the invention is to so construct the leer that the ends thereof are substantially sealed at all times, so that no air is permitted to enter except through adjustable ports, as may be found necessary 25 to bring about the required reduction in temperature; thereby not only conserving the heat given off by the glassware, but also preventing the entrance of drafts of air which by suddenly cooling the glassware 30 destroy the effect of the annealing process.

The invention also includes a novel means 35 for feeding the glassware to the conveyer; a new and improved means for operating the conveyer step by step and locking the same during the rest period; means for shifting the glassware from the downward run of the conveyer to the upward run thereof; means for accurately controlling the temperature of the leer; the elimination 40 of the intermediate oven; and numerous other advantages which will be apparent to one skilled in the art from the following detailed description when taken in connection with the accompanying drawings, in which:

45 Figure 1 is a side elevation of the leer; parts being broken away to more clearly show the construction.

Figure 2 is a side elevation of the upper portion of the apparatus.

50 Figure 3 is a side elevation of the lower portion of the apparatus, and being a continuation of Figure 2.

Figure 4 is a front elevation of the upper portion of the apparatus.

55 Figure 5 is a front elevation of the lower

portion of the apparatus, and being a continuation of Figure 4.

Figure 6 is a vertical sectional view of the upper portion of the apparatus.

Figure 7 is a fragmentary sectional view 60 of the carriage for operating the tray; the section being taken on line 7—7 of Figure 6.

Figure 8 is a plan view on an enlarged scale of the tilttable closures for sealing the space about the conveyer chains to prevent 65 entrance of air; and

Figure 9 is a vertical sectional view taken on line 9—9 of Figure 8.

Referring to the drawings more in detail, numeral 1 indicates the walls of the leer, 70 which are formed of any desired insulating material, such as cork brick. Mounted on the top of the oven walls is a muffle 2, which is preferably heated by gas jets, and which is provided on its outer sides with heat- 75 insulating walls 3.

A vertical endless conveyer, indicated generally by numeral 4, is mounted to travel downwardly through the leer and upwardly on the outside thereof. This conveyer is 80 provided with a series of suitably spaced shelves, or leer pans, for carrying the glassware. The glassware is supplied to the shelves at the feeding station, and the conveyer moves slowly, step by step, downwardly through the leer. After passing through the leer the glassware is automatically transferred to the upward run of the conveyer; the glassware then being carried upwardly to a convenient point for unloading. 85 The construction of the ware-carrying conveyer, and the mechanism for operating the same will first be described.

Construction and operation of the ware-carrying conveyer. 95

Transverse shafts 5 and 6 are mounted above and below the leer respectively, and transversely thereof. Two spaced chain wheels are mounted on each of these shafts, 100 and an endless chain, indicated by numeral 7, travels over each pair of chain wheels. The endless chains are provided with rollers 8 that fit into recesses 9 formed in the periphery of the chain wheels. The rollers 105 8 pass between a pair of angle irons, 8' arranged in the leer walls; the function of the rollers and angle irons being to prevent any tilting of the leer pans carried by the links. 110

A plurality of shelves or leer pans 10 are rigidly attached to the links of the endless chains in any preferred manner; and, if desired, webs may be employed to strengthen the connection between the pans and the links of the chains. Of course, the leer pans may be of various constructions, but it is preferred that they be formed with a downwardly extending flange and a plurality of transverse ribs, as indicated in Figure 4. As the position of the pans is reversed on the upward run of the conveyor, the flanges and ribs will be upturned; and thus when the trays are shifted from the downward run 15 to the upward run of the conveyor the trays will rest on the flanges and ribs, thereby aiding in the cooling of the glassware as it passes to the unloading position.

In order that the endless chains may be maintained taut at all times, the bearings for the lower shaft 6 are slidably mounted, and the weight 10 tends to draw the bearings downwardly, thereby keeping a constant tension on the chains.

For operating the ware-carrying conveyor a motor 11 is provided, and this motor drives a worm wheel 11' which is adapted to be operatively connected to a transverse shaft 12 by means of a clutch 13. Fixed to the shaft 12, adjacent the opposite end thereof, is a member 14, which is provided on its outer wall with a cam track 15; the cam track being formed with a depression 16 therein. A shaft 17 has a weighted operating arm 18 fixed thereto, and also fixed to this shaft is an upwardly extending arm 19. Pivotedly attached to the arm 19 is a link 20, and the opposite end of this link is resiliently connected to the clutch-operating arm 21 by means of coil spring 22. The arm 21 is pivotally attached at its lower end to a bracket 23, and at its upper end the arm engages the clutch 13. The upper end of the arm 19 carries a roller 24 which rides 45 on the cam track 15.

The operation of the mechanism thus far described is as follows:

When a tray of glassware has been placed on one of the conveyor shelves, in a manner 50 to be hereinafter described, and the operator desires to move the conveyor one step, it is only necessary for him to lift the operating lever 18, thereby moving the arm 19 to the right (Figure 4); this movement 55 of the arm 19 frees the roller 24 from the depression 16 of the cam track, and at the same time throws the clutch 13 into operative position, so that the shaft 12 starts immediately to rotate, and the roller 24 rides 60 on the cam track 15, thus holding the clutch in operative position. The rotation of the shaft and cam will continue for one complete revolution and when the revolution has been completed the roller moves into the 65 depression 16 and the clutch is thereby

thrown into inoperative position, and the rotation of the shaft and cam ceases. It will be understood, of course, that the weight carried by the operating lever 18 causes the movement of the arms 19 to the left (Figure 70 4) to throw the clutch out of operation, when the depression 16 comes into alignment with the roller 24.

By reference to Figure 4, it will be seen that the shaft 5, which carries the chain 75 wheels, has a disk 25 fixed thereon and this disk is provided with a plurality of radial slots 26 and peripheral grooves 27, as clearly shown in Figure 2. The shaft 12, which is driven by the motor 11, carries an arm 28 (Figure 2) having a finger 29 adapted to engage in the radial slots and rotate the disk until the finger 29 passes clear of the radial slot. Of course, as soon as the finger clears the slot, the disk 25 and shaft 85 5 are no longer rotated; and for the purpose of locking the disk and shaft in this position the end of shaft 12 is provided with a locking segment 30 which engages in one of the peripheral grooves 27 of the disk 25, and 90 prevents any further rotation of the disk. It will be understood that after the arm 28 has made a complete revolution, and the finger 29 is ready to enter the next radial slot, the locking segment 30 will have moved 95 to a position to permit rotation of the disk 25 and shaft 5.

It is, thus seen that when the operating lever 18 is lifted the clutch 13 is thrown into operative position, and remains in this position until the shaft 12 has made a complete revolution, whereupon the clutch is automatically thrown into inoperative position. During this revolution of the shaft 12 the arm 28 carried by the shaft engages one of 105 the radial slots, by means of the finger 29, and rotates the disk 25 and shaft 5 a predetermined distance to move the conveyor shelves one step; and as soon as the finger 29 is free of the radial slot 26 the locking 110 segment 30 engages one of the peripheral grooves and locks the disk 25 and the conveyor shaft 5 against further movement.

The next feature of the invention to be described will be the mechanism for feeding 115 the glassware to the leer.

Means for feeding glassware to the leer.
The leer is provided with a mouth 31 through which the glassware is fed to the 120 conveyor shelves 10. Mounted on the outside of the leer, adjacent the mouth 31, is a rectangular frame 32, on the top of which rests the tray 33 for receiving the glassware. A carriage 34 is mounted to travel 125 back and forth on the frame 32, and adjacent each side of the carriage is a series of pivotally mounted dogs 35. As clearly shown in Figure 6, these dogs are weighted at their lower ends, so that when they are 130

free they extend upwardly in an almost vertical position, so that the upper ends thereof extend above the frame, and are in a position to engage the tray and move it inwardly one step. Of course, appropriate stops, not shown, will be employed to limit the backward swinging movement of the dogs.

In the operation of feeding glassware to the leer a tray is placed on the frame 32 and this depresses all of the dogs that are under the tray. A row of glassware is now placed on the tray, as indicated by numeral 36 (Figure 6), and the carriage is moved inwardly, in a manner to be hereinafter described, by the engagement of the upstanding dogs with the outer wall of the tray. The tray is thus carried into the leer a predetermined distance, which distance will be substantially equivalent to the width of the glassware. The carriage is now moved back, thus freeing another set of dogs which engages the outer wall of the tray; and as soon as another row of glassware has been placed on the tray the operation is repeated to move the second row into the leer, and the operation is continued until the tray has been filled and moved entirely within the leer, where it rests on one of the shelves or leer pans 10.

Obviously, it is desirable to have the mouth 31 of the leer closed between the feeding operation; and for that purpose a vertically sliding door 37 is provided adjacent the mouth, the door being of such a width that it will fit down into the tray, to the rear of the last row of glassware that has been fed into the leer. Of course, the door may be of various constructions, but in the form illustrated herein the door is carried by a pair of spaced rods 38 which are slidably mounted in bearing brackets 39. These rods are connected to pivotally mounted counterbalanced arms 40 by means of links 41. The arms 40 are fixed to a shaft 42, and also fixed to this shaft is an operating lever 43 by which the shaft 42 is rotated to raise and lower the arms 40 and, through the connection already described, to thereby raise and lower the door 37.

In the operation of the feeding mechanism the door is first lifted, and immediately the carriage and tray carrying the glassware are moved inwardly one step; the door is then lowered into the tray and the carriage is moved backward to its position for the next feeding operation. It is desirable, of course, that a single means be provided to move the door and feeding mechanism in their proper sequence, and the means for accomplishing this will now be described.

A treadle 44 is suitably mounted for convenient control by the foot of the operator, and this treadle is pivotally connected to an

upwardly extending rod 45. The upper end of the rod 45 is slidably mounted in a block carried adjacent the end of the lever 43, and a coil spring 46 is mounted on the rod between the block and an adjustable collar 45'. It is thus seen that upon depressing the treadle 44 the rod 45 is raised, and, through the spring connection 46, the lever 43 is raised, thereby lifting the door 37. Upon further upward movement of the rod 45 the door will merely remain in its open position, while the rod slides on through its bearing in the lever 43 against the pressure of spring 46, as clearly shown in Figure 2. It is during this further upward movement of the rod that the feeding mechanism is operated, as will now be described.

A shaft 47 extends substantially half way across the front of the leer, beneath the feeder carriage, and fixed to one end of this shaft is an arm 48 which is located beneath the center line of the carriage, and this arm is pivotally connected to the carriage by means of a link 49. Fixed to the opposite end of the shaft 47 is an arm 50, and this arm is pivotally connected to a block 51 by a pair of links 52; the block 51 being loosely mounted on the rod 45 so that the latter is freely movable therethrough. Also mounted on the rod 45, but fixed thereto, is a second block, indicated by numeral 53.

It is thus apparent that as the rod 45 is raised, by depressing the treadle 44, it will first cause the door 37 to be opened, the feeder carriage remaining stationary. Upon further upward movement of the rod the block 53 will strike the block 51, thereby raising the arm 50 and moving the arm 48 to the right (Figure 2), and this movement of the arm 48, through the link connection 49, causes the carriage to travel inwardly. As soon as the pressure is removed from the treadle 44 it is obvious that the operation of the parts will be reversed, so that the door will be lowered and the carriage moved back to its position for feeding in the next charge of glassware.

As the shelves or leer pans are fixed to the links of the conveyer chains, it is apparent that some means must be provided for shifting the trays of glassware from the downward run of the conveyer to the upward run thereof, and the means by which this is accomplished will now be described.

Means for shifting the trays from the downward run of the conveyer to the upward run thereof.

A pusher 54 is mounted to reciprocate across the conveyer shelves, and this pusher is carried by a pair of pusher rods 55 mounted between sets of rollers 56, 56. A shaft 57 extends across the front of the leer, and is mounted in bearing brackets carried by the leer frame. Fixed to each

end of this shaft is a downwardly extending arm 58, and these arms are pivotally connected to the pusher rods 55 by means of the links 59. The shaft 57 is counterbalanced by a weighted arm 60.

One of the arms 58 is in the form of a bell crank lever, and the arm 61 of this bell crank lever is pivotally connected to a link 62, as clearly shown in Figures 3 and 5. The link 62 is pivotally connected at its upper end to the arm 63 of a bell crank lever construction, the bell crank lever being mounted on a stub shaft 64 carried by the leer frame. The other arm of the bell crank lever, indicated by numeral 65, carries a roller 66 which is received in a cam groove 67 provided in the member 14 which carries the previously described cam track 15; the two cams being located on opposite sides of the member 14. The cam groove 67 is shown in Figure 2 in two of its positions: one position being indicated in heavy broken lines, and the other position being indicated in light dash and dot lines.

The cam groove 67 must be of such a contour that it will cause one reciprocation of the pusher during a complete revolution of the cam, and, of course, that portion of the cam groove which causes the reciprocation must be so located that the reciprocation will occur while the conveyer is at rest and locked.

Referring to Figure 2, the finger 29 is just entering one of the radial slots 26 of the disk 25, and hence the conveyer is just beginning to move. During this movement the roller 66 simply rides in the concentric portion of the cam groove, so that no motion is imparted to the bell crank lever. From an inspection of the cam groove 67 it is obvious that the roller 66 will continue in the concentric groove until after the finger 29 has passed clear of the radial slot, whereupon the conveyer is locked against further movement. During this period of rest the cam continues to rotate, of course, and the roller passes through the irregular portion of the cam groove, whereby the roller 66 and arm 65 are moved to the right (Figure 2) to the position shown in dot and dash lines, and then back to normal position.

When the arm 65 is moved to the right, the other arm 63 of the bell crank lever is lifted, and, through the link connection 62, the arm 61 of the bell crank lever fixed to the shaft 57 is also lifted. This movement of the arm 61 causes the arms 58 to swing inwardly, and, through the link connection 59, the pusher is forced across one of the conveyer shelves, thereby pushing the tray 33 over onto its opposite shelf on the upward run of the conveyer. It will be understood, of course, that the operation is merely reversed when the roller 66 and arm 65 are

moved to the left (Figure 2), so that the pusher is withdrawn and remains at rest until the conveyer is moved downwardly another step and locked.

For the purpose of assisting in the support of the trays while they are being transferred to the upward run of the conveyer, a stationary shelf 68 is mounted on the leer frame, between the runs of the conveyer; and, if desired, this shelf 68 may be vertically adjustable, as shown in Figure 3, for the purpose of correcting slight inaccuracies in alignment.

Means for sealing the top and bottom of the leer.

As previously stated herein, one of the purposes of this invention is to conserve the heat of the leer, and to assist in accomplishing this result the top and bottom of the leer are sealed. Of course, the invention is not limited to the specific means illustrated herein, but in the preferred embodiment of the invention spring-pressed-seal plates are provided, the plates being held against the edges of the leer pans or shelves, and thereby preventing, to a large degree, the passage of air to or from the leer. The construction of the sealing means is the same at the top and bottom of the leer, and Figure 1 shows the general arrangement, while Figure 6 shows the construction more in detail. The sealing plates are indicated by numeral 69, and these plates are carried by rods 70, which are slidably mounted in the leer walls, and are pressed inwardly by means of coil springs 71. Outwardly extending flanges 72 and 73 are provided at the top and bottom, respectively, of the seal plates 69 for preventing the passage of air between the seal plates and the leer walls, as clearly shown in Figure 6. It is to be noted here that three of the shelves 10 are positioned between the sealing walls when the conveyer is stationary, thereby providing two dead air spaces to further aid in the conservation of the leer heat. During the movement of the conveyer there will always be at least two of the shelves between the sealing walls, and thus there is always one dead air space provided.

At the front and back of the leer the seal plate will be in a single piece extending the entire width of the leer; but, on account of the conveyer chains, it will be understood that it will be necessary to divide the side plates into two sections. For sealing the space around the conveyer chains a pair of tiltable closure members is employed, as illustrated in Figures 8 and 9. The tiltable closure members are indicated by numerals 74, and they are normally held in a horizontal position by means of weighted arms 75. It is obvious from an inspection of Figures 8 and 9 that as the chains move downwardly step by step the rollers 8, carried by the

chains, will tilt the closure members to open position, and as soon as the roller has passed the closure members will return to their normal position, thus closing the passage until 5 the next movement of the conveyer.

For the purpose of controlling the temperature of the lower portion of the leer, the front and rear walls are provided with a series of openings, indicated by numeral 76, 10 and the admission of air through these openings is controlled by means of a sliding damper 77 provided with a series of openings 78. In place of this construction any other desired means may be employed; and, 15 if preferred, the air admission means may be thermostatically controlled.

The construction of the various elements of the leer and their operation have been described in detail, and the general operation 20 of the entire apparatus will now be briefly described.

The glassware is taken from the mold or press and immediately placed in the tray. As soon as one row of glassware is on the 25 tray the operator depresses the treadle 44, thereby raising the door 37 and pushing the tray into the leer such a distance that when the door 37 descends the row of glassware is just behind it and inside of the leer. The 30 pressure is then removed from the treadle, and the door is lowered to closed position, and the feeding carriage is moved back to position for feeding the next row of glassware. This operation is repeated until the 35 tray has been filled and moved entirely into the leer, where it rests on one of the shelves or leer pans carried by the endless conveyer.

As soon as the filled tray is within the leer 40 the operator lifts the lever 18, thereby throwing in the clutch 13, which causes the conveyer and glassware carried thereby in the leer to be moved downward one step in the manner hereinbefore described. After the 45 conveyer has moved one step it is locked against further movement, but the member 14, carrying the cams, continues to rotate until a complete revolution has been made, whereupon the clutch is automatically thrown 50 into inoperative position. During this subsequent rotation of the member 14 the cam groove 67 functions, thereby causing the pusher 54 to transfer the lowermost tray of glassware from the downward run of the 55 conveyer to the upward run thereof, as described hereinbefore in detail. The trays of glassware are now carried upward by the conveyer to a convenient point for unloading. In this connection it is to be noted 60 that, as both runs of the conveyer are normally loaded with glassware, the conveyer is balanced to a large degree, and hence very little power is required for its operation.

As previously mentioned herein, the glass-

ware is fed to the leer directly from the 65 mold or press, and the necessity for the intermediate oven, now in common use, is thereby eliminated; which obviously results in a very great saving.

Each layer of hot articles that is placed in 70 the leer has beneath it another layer of articles at only a slightly lower temperature than the first layer, and the heat that is radiated from this lower layer functions as a baffle or barrier to prevent the rapid radiation 75 of heat from the upper layer. While I have simply mentioned the layer directly beneath the layer last introduced, it will be obvious that there is a whole series of layers below the uppermost layer, and each one of 80 these series functions in the same manner to reduce radiation from the uppermost article, though, of course, the layers further removed from the uppermost layer do not exert this influence to the same extent as do 85 the layers immediately beneath it. It will also be understood, of course, that while all of the heated articles below the uppermost layer of articles tend to prevent radiation of 90 heat from that article, so, too, is radiation of heat from lower articles retarded by the articles below them which have a temperature only slightly lower.

It will also be understood that as the articles are introduced at the top of the leer in 95 a heated condition and slowly moved downwardly through the chamber after passing through the muffle, the contents of the chamber will give up their heat gradually as they move down and the air thus heated will rise 100 to the top of the leer, thereby contributing to the maintenance of the temperature of the upper portion of the chamber.

In order to properly anneal glass ware, the articles should be gradually cooled from 105 about 950 degrees to about 600 degrees; and from the foregoing description it will be apparent that the temperature of the leer disclosed herein will naturally be the highest at the top of the leer, and that this temperature will be decreased very gradually toward the bottom of the leer.

It is also thus apparent that in annealing glass ware in the manner described herein very little, if any, heat other than the residual heat of the articles is necessary. If the articles were introduced at the bottom of the leer and were carried upward, the heat given off by the article would rise to the top of the leer and consequently the articles would be 115 discharged from the leer at substantially the same temperature at which they entered. And it is also true that if a horizontal leer were employed the operation would be by no means the same, and there would not be the 120 same even distribution of heat at a gradually lowering temperature; and, further, it would be necessary to supply a large amount

of heat to the leer, for the horizontal leer does not present the same economical arrangement as this vertical leer wherein the heat given off by the articles being annealed rises to the top to contribute to the maintenance of the temperature of the upper portion of the leer.

In the present construction the ends of the leer are sealed, and, furthermore, the leer pans are only slightly spaced from the walls of the leer, so that it is impossible for chilling drafts to sweep through the leer; and accordingly in the present construction the glassware is subjected to an even temperature, which is gradually decreased as the ware descends, thereby producing the best annealing effect.

From the foregoing it will be apparent that the leer construction described herein will result in a great saving of floor space; that it will handle the glassware in a most efficient manner; that it will require a minimum of auxiliary heat; and that the glassware will be annealed under conditions producing the best results.

What I claim as new and desire to secure by Letters Patent is:

1. In a vertical leer for annealing glassware, an endless conveyer having one run thereof adapted to move downwardly through the leer, a plurality of leer pans carried by the conveyer, and means co-operating with the leer pans for sealing one end of the leer.

2. In a vertical leer for annealing glassware, an endless conveyer having one run thereof adapted to move downwardly through the leer, a plurality of leer pans carried by the conveyer, and means co-operating with the leer pans to form a substantial seal at the upper end of the leer.

3. In a vertical leer for annealing glassware, an endless conveyer having one run thereof adapted to move downwardly through the leer, a plurality of leer pans carried by the conveyer, and means co-operating with the leer pans to form a substantial seal at the top and bottom of the leer.

4. In a vertical leer, for annealing glassware, an endless conveyer for carrying the glassware downwardly through the leer, said conveyer passing into the leer through the top thereof and out of the leer through the bottom thereof and means for forming a substantial seal at the top and bottom of the leer.

5. In a vertical leer for annealing glassware, an endless conveyer for carrying the glassware downwardly through the leer, said conveyer passing into the leer through the top thereof and out of the leer through the bottom thereof means for forming a substantial seal at the top and bottom of the

leer, and means for admitting air to the lower portion of the leer.

6. In a leer for annealing glassware, an endless conveyer adapted to move through the leer, a plurality of leer pans carried by the conveyer, and spring-pressed plates engaging the pans at one end of the leer; whereby a substantial seal is formed.

7. In a leer for annealing glassware, an endless conveyer having one run thereof adapted to move downwardly through the leer, a plurality of leer pans carried by the conveyer, and spring-pressed plates arranged adjacent the top and bottom of the leer, said plates co-operating with the leer pans to form seals.

8. In a vertical leer for annealing glassware, an endless conveyer having one run thereof adapted to move downwardly through the leer, a plurality of leer pans carried by the conveyer, means co-operating with the leer pans to form a substantial seal at one end of the leer, the construction and arrangement being such that at least two of the leer pans will be within the sealing means at all times, whereby a dead air space is formed.

9. In a vertical leer for annealing glassware, an endless conveyer having one run only thereof adapted to move through the leer, and substantially a Geneva-stop mechanism for moving the conveyer step by step and locking the conveyer during its periods of rest.

10. In a leer for annealing glassware, an endless conveyer having one run only thereof adapted to move through the leer, a disk operatively associated with one of the conveyer shafts, said disk being provided with a plurality of radial slots and peripheral grooves, a shaft, means carried by said shaft to engage in one of the radial slots to rotate the disk one step, and means also carried by said shaft for engaging one of the peripheral grooves to lock the disk during its period of rest.

11. A leer, an endless conveyer for carrying articles through the leer, means for operating the conveyer step by step, said means including a rotary member, a motor for operating the rotary member, a clutch interposed between the motor and rotary member, means for throwing the clutch into operative position, and means for automatically throwing the clutch into inoperative position after a complete revolution of the rotary member.

12. A leer, an endless conveyer for carrying articles through the leer, means for operating the conveyer step by step, said means including a rotary member, a motor for operating the rotary member, a clutch interposed between the motor and the rotary member, means for throwing the clutch into

- operative position, a cam for holding the clutch in operative position during a complete revolution of the rotary member, and means for throwing the clutch into inoperative position at the end of a complete revolution of the rotary member. 5
13. In a vertical leer for annealing glassware, an endless conveyer having one run thereof adapted to move through the leer, a plurality of leer pans carried by the conveyer, and reciprocating means for removing the glassware from the leer pans. 10
14. In a vertical leer for annealing glassware, an endless conveyer having one run thereof adapted to move downwardly through the leer, a plurality of leer pans carried by the conveyer, and means for shifting the glassware from the downward run of the conveyer to the upward run thereof. 15
- 20 15. In a vertical leer for annealing glassware, an endless conveyer having one run thereof adapted to move downwardly through the leer, a plurality of leer pans carried by the conveyer, trays adapted to be placed on the leer pans, and means for shifting the trays from the downward run of the conveyer to the upward run thereof. 25
- 30 16. In a vertical leer for annealing glassware, an endless conveyer having one run thereof adapted to move downwardly through the leer, means for shifting the glassware from the downward run of the conveyer to the upward run thereof, and means located between the runs of the conveyer for supporting the glassware during its transfer. 35
- 40 17. In a vertical leer for annealing glassware, an endless conveyer having one run thereof adapted to move downwardly through the leer, means for operating the conveyer step by step, means for shifting the glassware from the downward run of the conveyer to the upward run thereof, said means being operable during the periods of rest of the conveyer. 45
- 50 18. In a vertical leer for annealing glassware, an endless conveyer having one run thereof adapted to move downwardly through the leer, a rotary member for operating the conveyer step by step, a cam carried by the rotary member, a pusher for removing the glassware from the downward run of the conveyer, and means associated with the cam for operating the pusher during the period of rest of the conveyer. 55
- 60 19. In a vertical leer for annealing glassware, an endless conveyer having one run thereof adapted to move downwardly through the leer, a rotary member for operating the conveyer step by step, a cam carried by the rotary member, means associated with said cam to stop the rotation of the member at the end of a complete revolution, a second cam carried by the rotary member, 65 a pusher for removing the glassware from
- the downward run of the conveyer, and means associated with the second mentioned cam for operating the pusher during the period of rest of the conveyer. 70
20. In a leer for annealing glassware, an endless conveyer for carrying glassware through the leer, an inlet and an outlet for the conveyer at the ends of the leer, an opening in the side of the leer, transferring mechanism by which trays of glassware are transferred to the said conveyer through the said opening, a closure for said opening, and means for timing the operation of said closure and said transferring mechanism. 75
21. In a leer for annealing glassware, an endless conveyer for carrying glassware through the leer, the leer being provided with a mouth, a door for closing the mouth, means for feeding glassware into the leer step by step, and means for operating the door and feeding means in proper sequence. 80
22. In a vertical leer for annealing glassware, an endless conveyer having one run thereof adapted to move downwardly through the leer, the leer being provided with a mouth, a door for closing said mouth, a frame adjacent the mouth, a tray for receiving the glassware and adapted to rest on the frame, means for raising and lowering the door, and means operatively connected with the door-operating means for moving the tray step by step into the leer. 90
23. In a vertical leer for annealing glassware, an endless conveyer having one run thereof adapted to move downwardly through the leer, the leer being provided with a mouth, a door for closing the mouth, means for operating the door, means for feeding glassware through the mouth to the conveyer, and a lost-motion connection between the door-operating means and the feeding means, whereby the parts operate in proper sequence. 95
24. In a vertical leer for annealing glassware, an endless conveyer having one run thereof adapted to move downwardly through the leer, the leer being provided with a mouth, a frame adjacent the mouth, a tray adapted to rest on the frame, a carriage mounted for reciprocation in the frame, means for reciprocating the carriage, and a series of pivotally mounted dogs for engaging the tray to move the same into the leer step by step. 100
25. In a vertical leer for annealing glassware, an endless conveyer having one run thereof adapted to move downwardly through the leer, means for moving the conveyer step by step, means for feeding glassware to the downward run of the conveyer, and means for shifting the glassware from the downward run of the conveyer to the upward run thereof. 110
26. In a vertical leer for annealing glassware, an endless conveyer having one

run thereof adapted to move downwardly through the leer, leer pans carried by the conveyer, means co-operating with the leer pans to form a seal at the top and bottom of the leer, means for feeding glassware to the leer pans, and means for shifting the glassware from the downward run of the conveyer to the upward run thereof.

27. In a vertical leer for annealing 10 glassware, an endless conveyer adapted to

move through the leer, a muffle for heating the upper portion of the leer, and means for sealing the upper end of the leer.

28. In a vertical leer for annealing glassware, an endless conveyer adapted to 15 move through the leer, a muffle for heating the upper portion of the leer, the exterior of said muffle being insulated, and means for sealing the top and bottom of the leer.

ROBERT GOOD.
